UNITED STATES PATENT OFFICE.

JOHN CARSON, OF CENTERPORT, NEW YORK.

SHOCK-ABSORBING ATTACHMENT.

1,070,114.

Specification of Letters Patent. Patented Aug. 12, 1913.

Application filed February 21, 1913. Serial No. 750,031.

To all whom it may concern:

Be it known that I, JOHN CARSON, a citizen of the United States, residing at Centerport, in the county of Suffolk and State of New York, have invented new and useful Improvements in Shock-Absorbing Attachments, of which the following is a specification.

This invention relates to improvements in shock absorbing attachments for vehicle springs, and it proposes a device which may be applied with facility to an elliptic spring of ordinary construction.

The principal object of the invention is to provide a device for substantially eliminating the minor shocks or vibrations which occur on the recoil and counter-recoil of the spring. The ordinary elliptic spring is proportioned to withstand heavy shocks and for this reason there is, of necessity, a certain sacrifice of resiliency, with the result that in the action of the spring certain minor tremors are set up which detrimentally affect the engine and the driving gear. The device which forms the subject of the present invention is intended to reduce these minor tremors and to thereby improve the riding qualities of the vehicle.

Further objects of the invention are to provide an attachment of the character described which shall be compactly organized, of self-contained nature, inconspicuous, and readily applicable to existing types of vehicle springs.

An embodiment of the invention is illustrated in the accompanying drawings, wherein:

Figure 1 is a side elevation showing the attachment applied in connection with an elliptic spring of ordinary construction; Fig. 2 is a vertical sectional view of the attachment *per se*; Fig. 3 is a vertical sectional view of the attachment in a plane at right angles to the plane of Fig. 2; Fig. 4 is a horizontal sectional view on the line 4—4 of Fig. 2.

Similar characters of reference designate corresponding parts throughout the several views.

The vehicle spring shown is of the ordinary elliptic form, comprising the lower section A associated with the axle B, and the upper section C associated with the vehicle frame D.

The attachment which forms the subject of the present invention and is designated generally by the letter E comprises relatively movable parts which are associated with the respective spring sections, and means for putting a drag on the movements of these parts relatively to one another. Thus, the embodiment shown comprises a casing 1 which is associated with the axle B, and a block 2 which is associated with the spring section C, (or it might be the vehicle frame D), being connected thereto by a rod 3. The block 2 reciprocates in the casing 1 consequent to the tremors or vibrations of the spring sections and for the purpose of putting a drag on said block in its reciprocatory action, spring pressed shoes 4 are provided, the arrangement being such that the pressure with which the shoes 4 bear on the block 2 increases proportionately to the extent of movement of said block.

The shoes 4 are arranged in pairs at opposite sides of the casing 1 and in upper and lower relation, the shoes of each pair being mounted upon a common transverse pivot pin 5. The shoes 4 extend in converging relation toward the upper and lower heads of the casing, and the block 2, which is arranged between said shoes, has at its sides reversely inclined faces 6 which bear against the shoes 4, the arrangement being such that the upper inclined faces 6 coact with the upper shoes 4 and the lower inclined faces 6 coact with the lower shoes 4.

For the purpose of establishing a relatively strong frictional engagement between the shoes 4 and the block 2, each shoe is acted on by a spring 7. In the embodiment shown, these springs are of the expansive coil type and are arranged near the upper and lower heads 8 of the casing 1, being centered within retaining cylinders 9 which are carried by the walls of said casing, adjoining said shoes. The outer ends of the cylinders 9 are closed by threaded caps 10 which may be utilized to regulate the tension of the springs 7.

The walls of the casing 1 adjoining the shoes 4 may be provided at their sides with flanges 11 fashioned to engage the outer edge portions of the shoes 4 and to thereby limit the outward movement of said shoes. The shoes 4 may be provided at their sides with inwardly extending flanges 12 which

overlie the block 2, and in the event of any looseness of the parts, serve to accurately center said block with relation to said shoes.

The block 2 normally occupies the position 5 shown in Fig. 2, wherein it is located symmetrically with relation to the upper and lower shoes 4 and its faces 6 are in engagement with the corresponding shoes. When the spring sections are vibrant and the block 10 2 reciprocates in the casing 1, the shoes 4 will be moved against the tension of their springs 7. A movement of the block 2 from the position of Fig. 2 toward the upper end 15 of the casing 1 causes an outward movement of the upper shoes 4, accompanied by a progressive increase of the pressure of said shoes on said block. A similar action is effected in the case of the lower shoes 4 when the block 2 moves from the position of Fig. 2 to 20 the lower end of the casing 1. Of course, when the block 2 moves toward the center of the casing 1, the springs 7 move the shoes 4 inwardly. In this way the shoes 4 exert a constant drag on the block 2 in its reciprocatory movements, and it follows that the minor vibrations of the spring sections A and C are substantially reduced.

For the purpose of supporting the casing 1, it is preferred to use a bracket 13 which 30 is secured to the lower head of said casing and has formed therewith a hook 14 for engagement about the axle. The hook 14 firmly supports the casing 1 and its associated parts from the axle and yet allows of

such slight pivotal displacements of said casing as may be attendant upon the action of the spring sections A and C. 35

Having fully described my invention, I claim:

1. A shock absorbing attachment comprising a casing, a block movable therein, shoes mounted in pairs at opposite sides of the block for frictional engagement therewith, the shoes of each pair being mounted upon a common pivot and springs bearing against 45 the shoes adjacent their outer ends and also having bearing against the adjacent walls of the casing, in combination with an elliptic spring, the sections of which are connected to said casing and to said block respectively. 50

2. A shock absorbing attachment comprising a casing, a block movable therein, shoes mounted in pairs at opposite sides of the block for frictional engagement therewith, the shoes of each pair being mounted upon a 55 common pivot, springs bearing against the shoes adjacent their outer ends, spring retaining cylinders set into the walls of the casing, and removable caps forming closures for the outer ends of the cylinders and 60 against which the springs bear.

In testimony whereof I have hereunto set my hand in presence of two subscribing witnesses.

JOHN CARSON.
